UNITED STATES PATENT OFFICE.

LINDOL FRENCH, OF EAST PEPPERELL, MASSACHUSETTS.

ELECTRICALLY-HEATED APPLIANCE.

1,378,850.

Specification of Letters Patent. Patented May 24, 1921.

Application filed July 17, 1919. Serial No. 311,429.

To all whom it may concern:

Be it known that I, LINDOL FRENCH, a citizen of the United States, and resident of East Pepperell, county of Middlesex, Commonwealth of Massachusetts, have invented an Improvement in Electrically-Heated Appliances, of which the following description, in connection with the accompanying drawings, is a specification, like characters on the drawings representing like parts in each of the several views.

This invention relates to electrically heated appliances and apparatus and more particularly to means associated therewith for automatically controlling the supply of current to the appliance to prevent overheating thereof. While having other and more general fields of usefulness the invention is well adapted for utilization with an electrically heated flat-iron, and it is herein so shown for illustrative purposes. The foregoing and other objects and advantages of the invention will more fully appear from the following detailed description, and the distinctive features of novelty will be pointed out in the appended claims.

Referring to the drawings:

Figure 1 is a lengthwise vertical section of an electrically heated flat-iron equipped with my invention;

Fig. 2 is a plan view with the handle removed and with portions sectioned away to show interior construction;

Fig. 3 is a partial side view with a part in section showing a modified form;

Fig. 4 is an end view with a part broken away of the form shown in Fig. 3;

Fig. 5 is a partial elevation showing a casting member of Fig. 3 removed;

Fig. 6 is a side elevation with a part broken away showing another embodiment of the invention;

Fig. 7 is a plan view of the form shown in Fig. 6 with parts broken away;

Fig. 8 is a transverse section through the rear portion of the flat iron; and

Fig. 9 is a detail perspective view showing enlarged certain parts of the mechanism of Fig. 8.

10 indicates the base of an electrically heated flat-iron equipped with a usual housing 11 thereover with a suitably disposed electric heating element 12 shown as a coil of resistance wire directly over the base 10 and 15 with a usual slab or block 13 in the upper part of said housing over the heating ele-

ment, this slab being commonly made of iron or other material adapted to add requisite weight to the flat-iron and to serve as a heat conserving and equalizing element. 60 The handle 14 is shown as secured to the slab 13 by the bolts 15 while the slab 13 is held assembled with the base by one or more bolts 16. 17, 18 designate the external contact terminals with which the ends of the 65 heating coil 12 are engaged, these being shown as usual spaced apart metal pins adapted to be engaged by a cord socket. In accordance with my invention I provide a shunt circuit 19 between the terminals 17, 18 70 which has included therein a circuit cut-out shown in Figs. 1 to 5 as a blow-out fuse 20. As best seen in Fig. 2 this fuse is included both in said shunt circuit and in the main circuit which goes through the heating element, i. e., the shunt circuit branches off from the main circuit beyond said fuse. This shunt circuit includes a strip or bar 21 of so-called "thermostatic" metal which is fixed at one end at 21^a and has its other end 75 free to swing into engagement with a relatively stationary contact 22. This strip 21 may be composed of two layers of different metals having different co-efficients of heat expansion such for example as a copper alloy 80 for one thereof having a relatively high co-efficient of expansion, and a nickel steel alloy for the other thereof with a relatively low co-efficient of expansion. These metal layers may be secured together in any suitable way 85 either by welding or by riveting or otherwise, it being understood that the particular character of this composite metal strip *per se* forms no part of the invention. The contact 22 which is included in the shunt circuit 19 90 is preferably adjustable with reference to the strip 21 and for this purpose it is shown as having an insulated mounting on a post or pin 23 extending laterally inward from the side of the housing with an adjusting 95 head 24 therefor projecting outward to the exterior of the housing. In use, the strip 21 normally occupies the position shown in Fig. 2, i. e., with its free extremity separated by some little distance from the contact 22 so that the shunt circuit of which said strip and contact form the terminals, is broken. Whenever the iron becomes excessively hot for any reason such as by being left unused for some little time and with the 100 current on so that it would be apt to scorch or injure the goods, this abnormal heat acts 105

on the thermostatic strip 21 causing the same to flex so that it comes into engagement with the contact 22 thus closing the shunt circuit which results in blowing out the fuse 20 and hence cutting out not only the shunt circuit but also the main circuit through the heating element until the fuse is renewed. The fuse 20 is preferably located in convenient position for renewal at the top of the housing and the thermostatic strip 21 is preferably and as shown located close to and just above the base 10 so as to be most readily responsive to changes in the heat thereof.

15 It is also practicable to employ the present automatic cut-out with flat-irons already in use. For this purpose I provide a housing 25 which may be secured to the rear end of the flat-iron, as shown by means of screws 26 passed through and engaging lugs 27 at each side thereof. This housing is equipped with auxiliary terminal pins 28, 29 adapted to be engaged by the cord socket as usual. One of these pins shown as the pin 28 is directly engaged with one of the pins 170 of the flat-iron as regularly constituted. From this terminal pin 170 a shunt circuit 19' leads to a thermostatic strip 21' similar to the strip 21 already described and anchored at one end 30 to the housing as indicated at 21^b. A relatively fixed contact 22' is mounted in position to be engaged by the strip 21' when it is flexed by abnormal heat. This contact 22' is connected with the other terminal pin 35 180 of the iron as regularly equipped and it is also connected through the fuse 20' with the auxiliary terminal pin 29. With this organization it will be understood that the shunt circuit 19' is normally open and 40 that upon abnormal heat in the iron the strip 21' will engage the contact 22' completing the shunt circuit which will blow the fuse 20' and thus open the connection from the supplemental contact pin 29 to the regular contact pin 180 of the iron. The contact 22' may also in this case be made adjustable toward and from the strip 21' by having the same clamped in place by a screw 30 which may be adjusted in a slot 31 of the housing 25. Instead of using a blow-out fuse I may employ other means for breaking the main circuit through the heating element by the use of a shunt circuit controlled as described and in Figs. 6, 7 55 and 8 I show the use of an electro-magnet for this purpose. In this form the arrangement of the heating element and of the thermostatic contact strip 21 may be precisely as already described and arranged to control a shunt circuit 19'' in the same manner. This shunt circuit instead of having a fuse therein includes an electro-magnet 32, the armature 33 of which is connected with one of the terminal posts 18 of the iron through the connection 34 and from which the shunt circuit

branches. The armature 33 when retracted, i. e., when the magnet is deenergized engages a fixed contact 35 which is in the main circuit and leads from an end of the resistance element as indicated at 36. With this organization upon abnormal heating such as, to flex the strip 21 and close the shunt circuit 19'', the attraction of the armature 33 will break the main circuit by separating the contacts 33-35. The armature thus 75 moved is held in circuit breaking position by suitable means which may be of various forms but is herein shown as a spring detent 37 fixed to the housing and equipped with a shoulder which is adapted to snap in 80 behind the armature and hold it in circuit breaking position after it is moved to such position by the magnet. This detent may have a projecting finger 37^a extending up through the housing for convenient hand 85 actuation to trip said detent when it is desired to again set the iron in operation and reenergize the heating element. I am aware that the invention may be embodied in other specific forms without departing from the 90 spirit or attributes thereof, and I therefore desire the present embodiment to be considered in all respects as illustrative and not restrictive, reference being had to the appended claims rather than to the foregoing 95 description to indicate the scope of the invention.

Having described my invention, what I claim as new and desire to secure by Letters Patent is:

1. An electric flat iron comprising a heating element in a main circuit and in juxtaposition to the operative surface of said iron, a shunt circuit associated with said main circuit and having circuit closing means 105 therein responsive to an abnormal degree of heat in the iron and located within the iron relatively close to the operative surface thereof, and a circuit breaker in said main circuit responsive to energization of said 110 shunt circuit.

2. An electric flat iron or the like comprising a main circuit with a heating element therein and in juxtaposition to the operative surface of said iron, a shunt circuit 115 associated with said main circuit normally open but equipped with a device responsive to an abnormal degree of heat in the iron for closing the same, said device located within the iron and relatively close to its 120 operative surface, and a circuit breaker in said main circuit and also housed within the iron connected for operation by energization of said shunt circuit.

3. An electrically heated flat iron comprising 125 a main circuit having a heating coil therein, a shunt circuit associated with said main circuit having controlling contacts, one thereof borne by a strip of thermostatic metal responsive to abnormal heat for con- 130

trolling said contacts, said strip located within the iron and relatively close to its operative surface, and means for controlling the main circuit connected for operation by 5 energization of said shunt circuit.

4. An electrically heated flat iron comprising a circuit having a heating element therein located within the iron and relatively close to its operative surface and thermostatic means for controlling said circuit also located within the iron and relatively close 10 to its operative surface.

5. An electrically heated flat iron compris-

ing a circuit having a heating element there-in located within the iron and relatively 15 close to its operative surface, thermostatic means for controlling said circuit also located within the iron and relatively close to its operative surface, an automatic device for holding said circuit broken after the 20 breaking thereof by said thermostatic means and a manual trip for releasing said device.

In testimony whereof I have signed my name to this specification.

LINDOL FRENCH.
